UNITED STATES PATENT OFFICE.

JOHANNES MICHAEL SCHMIERER, OF GROSS-LICHTERFELDE, NEAR BERLIN, GERMANY, ASSIGNOR TO RADIO PATENTS CORPORATION, OF NEW YORK, N. Y., A CORPORATION OF NEW YORK.

ELECTRICAL OPERATING APPARATUS.

Application filed April 20, 1925, Serial No. 24,662, and in Germany November 19, 1923.

If the terminals of a glow light tube or lamp are subjected to a voltage which is not quite sufficient for the ignition of a glow discharge, a very feeble discharge current is produced which lights up the gas charge in the tube or lamp near the anode. This is quite the opposite of what takes place with a normal glow current namely, the formation of a glow layer near the cathode. The slope of a curve representing this "pre-glow-discharge" is essentially steeper than that of the normal glow-current and intersects the axis of the abscissa in contradistinction to the curve for the normal glow current.

According to the invention the required low terminal voltage is produced by series connection in any combination of electrical devices similar to the apparatus of Rahbek-Johnsen as shown for example in the drawings and specifications of the United States Patent No. 1,533,757, granted April 14, 1925. For more accurate adjusting any well known auxiliary means may be used such as additional series resistance, in some cases it may be combined with a shunt, and may also be arranged in the form of a so called voltage divider. When quite insignificant currents of any origin (for instance microphone currents, telegraphing currents and the like) are superposed on the pre-glow current they cause, owing to the steepness of their curve characteristics, considerable variations of the intensity of current which variations release very strong mechanical effects in the Rahbek-Johnsen arrangement.

In the accompanying drawings

Fig. 1 illustrates the characteristic curves of the pre-glow discharge and its relation to that of the glow discharge.

Fig. 2 shows in a diagrammatical view the use of the Rahbek-Johnsen arrangement according to the invention.

Referring to Fig. 1 the intensity of current is shown as function of the terminal voltage. When the terminal voltage is gradually increased the pre-glow discharge starts at the point A. With the increasing voltage the intensity of current increases very rapidly and the curve is decidedly linear. At the point B the discharge changes suddenly to a glow discharge, this phenomenon being accompanied by a considerable increase of the intensity of the current. In

the diagrammatic illustration this increase of the current intensity is shown much smaller than it is in reality. When the increasing of the voltage continues the current intensity increases also, however not so rapidly as at the pre-glow discharge. If the entire surface of the cathode is covered with glow-light, as supposed at point D, a further increase of the voltage causes only a slight increase of current intensity. If the voltage is then decreased a curve is obtained which coincides accurately with that at increasing voltage. At the point C, where the glow discharge has started, no reversing to the pre-glow discharge takes place, and the voltage can be still further reduced down to point E. If this point E is situated, as in Fig. 1, at the right of point A the glow discharge reverses to a pre-glow discharge, the current intensity dropping suddenly to the considerably lower value of the point F. If point E is at the left of point A the discharge current extinguishes completely. At the glow discharge the ignition voltage (point C) is higher than the extinguishing voltage (point E) and the curve begins and ends above the abscissa axis; at the pre-glow discharge ignition and extinguishing voltage coincides (point A) and the curve begins and ends on the abscissa axis. It is, therefore, possible to produce pre-glow current of any degree of feebleness, while for the glow discharge a low limit of voltage exists. The characteristic of the pre-glow discharge is extraordinarily steep and clearly linear, that of the glow discharge is much flatter and strongly bent, from which it results that the pre-glow discharge is superior to the glow discharge for all purposes of strengthening, exciting and detecting of oscillations. The values of the terminal voltage used in Fig. 1 comprises the loss of voltage in a series resistance without which glow-discharge tubes cannot be worked.

Instead of the series resistance any arrangement of Rahbek-Johnsen is used according to the invention. Fig. 2 shows this by way of example. Member *r* is a rotating cylinder of a semi-conductor, *f* a metal foil conducted over said cylinder, said metal foil being connected at the one end by a thread or the like with the centre of a diaphragm *s* and stretched at the other end by a weight *g*. Owing to the friction between cylinder and

foil a pull is exerted on the diaphragm. If a sufficient voltage is imposed between members r and f the electro-static attraction between the two produces a considerable increase of the resistance from friction and consequently of the pull exerted upon the diaphragm. If a feeble alternating voltage is superposed on this voltage the diaphragm vibrates in the rhythm of the same. The amplitude of these vibrations is the greater the stronger the superposed current is. As at the pre-glow discharge slight alterations of the voltage cause considerable alterations of the current intensity, a pre-glow discharge gap is inserted in the circuit, according to the invention, b is a battery, v a pre-glow-light tube, t the secondary winding of a transformer the primary winding of which forms a second circuit with a microphone m and a galvanic battery e . When the microphone is talked into electromotive forces are induced in the secondary winding of the transformer which are superposed on the voltage of the battery b whereby the diaphragm s renders strengthened reproduction of the electric forces of the microphone diaphragm. In order that the arrangement can act, in this manner, as a sound strengthener, the strength of the closed circuit current must correspond approximately to the point F in Fig. 1 and the amplitude of the superposed alternating voltage must not be greater than the projection of A B onto the abscissa axis. The voltage of the battery must therefore correspond approximately to the average value from the ignition voltage of the pre-glow-discharge and ignition voltage of the glow discharge. When, however, the battery voltage were equal to the ignition voltage of the pre-glow discharge the arrangement would act as detector (similar to an audion) and act only on the positive (or only on the negative) semi-waves of a superposed alternating current. It is, evidently, also possible to apply, instead of alternating current, continuous current impulses to permit the

use of the arrangement for the long-distance transmission of Morse signals. In this case a recording style instead of the diaphragm may be controlled, in a manner known per se, by the arrangement system Rahbek-Johnsen.

I claim:

1. Apparatus for the production of mechanical effects by electric currents comprising in combination an electrical glow discharge device, a circuit therefor, a source of electric energy in said circuit to furnish pre-glow current, electro-static members in the circuit, one of said members being movable, and means for superposing electric current on the pre-glow current of said glow lamp to permit variation of charge on said movable member.

2. The method of amplifying variations of electric current in a circuit which consists in supplying to a glow lamp therein current insufficient to cause a glow discharge in the lamp but sufficient to vary the potential of an electro-mechanical device.

3. The method of producing variations of mechanical force in a circuit which consists in supplying to a glow lamp a current insufficient to cause a glow discharge but sufficient for pre-glow discharge and for an electro-mechanical device in the circuit of the lamp, and utilizing said variations to produce mechanical power.

4. The method of detecting weak electrical oscillations which consists of applying them to a glow discharge device in the state of pre-glow discharge and thereby operating an electro-mechanical device.

5. The method of detecting weak electrical oscillations which consists of applying them to a glow discharge device at a potential of ignition of pre-glow discharge and thereby rectifying said oscillations, and applying the rectified oscillations to an electro-mechanical system.

In testimony whereof I affix my signature.

JOHANNES MICHAEL SCHMIDERER.
